United States Patent Office

Des. 176,059
Patented Nov. 15, 1955

176,059

SHOE

William E. Bolding, Newark, N. J., assignor to Johnston & Murphy, Newark, N. J., a corporation of New Jersey

Application February 14, 1955, Serial No. 34,497

Term of patent 7 years

(Cl. D7—7)

FIG. 1.

FIG. 2.

FIG. 3.

Fig. 1 is a top plan view of a shoe showing my new design.

Fig. 2 is a view in elevation of the inner side of the shoe of Fig. 1.

Fig. 3 is a view in elevation of the outer side of the shoe.

The dominant features of the design reside in the portions thereof shown in the accompanying drawings in full lines.

I claim:

The ornamental design for a shoe, as shown and described.
